MEANS AND METHOD OF CONTROLLING HIGH TENSION ELECTRICAL CIRCUITS

Thomas H. Rogers, New Canaan, and Gordon F. Bavor, Norwalk, Conn., assignors to Machlett Laboratories, Incorporated, Springdale, Conn., a corporation of Connecticut

Application May 2, 1956, Serial No. 582,252

7 Claims. (Cl. 250—98)

This invention relates to novel means and method of controlling high-tension electrical circuits and has particular reference to a system and method for controlling the operation of a high voltage energy responsive device whereby the device may be subjected to high voltage for precise ultra-short periods of time. Still more specifically this invention refers to a system and method for controlling the operation of a high voltage device such as an X-ray tube or the like so as to provide precisely timed ultra-short X-ray exposures in a selected range such as from one to five milliseconds.

In radiography the problems concerned with exposure duration are complicated where motion is involved in the subject matter and the problem of obtaining sharp, clear images becomes more and more complicated as the speed of motion increases. These problems are solved by the provision of more precise, shorter-interval timers and more X-ray producing power in a fine focus X-ray tube.

X-ray apparatus has become increasingly more capable in these respects. First, radiography at $\frac{1}{10}$ second was evolved and later $\frac{1}{60}$ second exposures became feasible. Fairly recently, however, it became desirable in work with heart radiography, particularly angiography, to obtain still shorter exposures in rapid succession, such as several per second.

Conventional high-powered generators have sometimes been used for this purpose and in these instances the basic circuit of the generator involved the opening and closing of a switch in the primary circuit of a high-tension transformer. This required careful consideration, in the development of timing and contacting systems, of the proper phasing of the instant of contact make and break with the sine-wave of the power supply. Such considerations generally limited possible time intervals to integral multiples of a one-cycle period of the A.C. power supply. Recently developed systems permit using an odd number of half-cycles, with minimum durations of $\frac{1}{20}$ second.

Other known prior art indicates that efforts have been made to obtain still shorter durations in the $\frac{1}{1000}$ -second range by making and breaking the circuit in the high-tension or secondary side of the circuit. This invention comprises improved and novel means and method of accomplishing the control of such exposures by switching in the high-tension circuit.

It is a primary object of this invention to provide a system for controlling the operation of high voltage energy responsive devices such as X-ray tubes or the like whereby the devices may be subjected to high voltage for precise ultra-short periods of time.

It is another object of this invention to provide a system for controlling the operation of an X-ray tube so as to provide precisely timed ultra-short exposures in a selected range such as from one to five milliseconds.

Another object is to provide a system of the above character which is adapted to existing diagnostic or other equipment.

A further object is the provision of a simplified system of the above character which requires low control-circuit

2

voltage and power requirements as well as relatively simple control circuitry.

A still further object is the provision of a system of the above character which embodies novel safety means for preventing damage to the high voltage device in the event of control voltage failure in the high voltage circuit.

Other objects and advantages of the invention will become apparent from the following description taken in connection with the accompanying drawings, in which

Fig. 1 is a simplified schematic diagram of the circuit of the switching system;

Fig. 2 shows the circuit details involved in supplying the various potentials required for the operation of the switching tube, and also shows the safety circuit, the grid return circuit, and the method of cutting the electronic switching system in or out;

Fig. 3 is a block diagram showing the various component parts of the system of the present invention as used with existing film changing equipment; and

Fig. 4 shows the basic circuit of a pulse generator usable with this system.

In the drawings the system is shown as being used for controlling the operation of an X-ray tube but it is to be understood that other high voltage energy responsive devices can be substituted for the X-ray tube if desired.

The circuit of the presently described system is employed in conjunction with a rectified X-ray generator having electrical energy storage means such as capacitors across the output whereby the generator, which is energized in advance of making the exposure, charges the capacitors to its full open-circuit voltage, and the exposure is then made at that voltage. The power for energizing the X-ray tube comes directly from the capacitors and, therefore, the need for synchronizing the exposure with the sine-wave power operating the transformer is eliminated. Also, in such a system, essentially square pulses are drawn from the capacitors.

A pulse-forming and timing circuit generates a control signal in the form of an essentially square voltage pulse, the width of which can be adjusted over a suitable range.

The signal is applied to the control grid of a switching tube through a pulse transformer which transmits square pulses five milliseconds or less in width without appreciable distortion. The pulse transformer also isolates the control circuit from the high-tension part of the system.

The control grid bias, screen grid potentials, and filament power for the switching tube are provided by an isolation transformer through suitable rectifiers and filters.

Embodying in the system also is a safety circuit which is provided to protect the equipment from damage in the event of loss of negative bias on the switch tube in case of power unit failure. This safety circuit consists of a voltage-sensitive relay across the bias supply which is actuated only when bias voltage is up to normal. This relay closes the circuit to a pilot lamp, the light from which actuates a photocell in a low voltage interlock circuit.

A further feature of the system is a special grid return circuit which minimizes driving power requirements by bypassing the current drawn by the control grid, during exposure periods of the X-ray tube, around the bias supply without the use of a shunting resistor.

All of the components which operate in the high-tension circuit, including the energy storage capacitors, pulse transformer, and the switching tube, with its bias and filament supply circuits, are adapted to be mounted in a single oil-filled tank for insulation reasons. This part of the system is interconnected between the rectified high voltage generator and the X-ray tube by shockproof cables.

Within the tank is also located an auxiliary multi-pole high-tension switch, solenoid-operated by remote con-

trol, by which the electronic switching system, including the energy storage capacitors, can be cut in or out of the circuit at will. Thus, the X-ray equipment can be used conventionally if desired.

Referring to the drawings, and more particularly to the schematic diagram of Fig. 1, it will be seen that a pulse-forming and timing circuit 10 is provided for generating a control signal in the form of an essentially square voltage pulse P which is applied to the control grid of a switching tube 11 through a pulse transformer 12. The pulse-forming and timing circuit 10, to be described later, allows adjustment of the pulse within a suitable range. The pulse transformer 12 transmits square pulses of controlled width such as about 5 milliseconds or less without appreciable distortion and also serves to isolate the control circuit from the high tension part of the system. The primary of pulse transformer 12 is connected directly into the circuit 10. A negative bias for the control grid of the switching tube 11 is provided by a suitable D.C. power supply 13. This negative bias is applied to the control grid of the switching tube through the secondary of pulse transformer 12. Special circuitry is provided to apply this negative cut-off bias to the control grid of the switching tube 11, as will be described more fully hereinafter with respect to Fig. 2. Positive screen grid potential in tube 11 is provided by a second D.C. power supply 14.

A high voltage generator 15 such as a four-valve full-wave bridge rectifier type as illustrated in Fig. 1 is utilized to charge two energy storage capacitors 16 in a balanced circuit as the primary source of energy for the X-ray tube 17. The high voltage switching tube 11 is in series with the positive side of the high voltage generator circuit to the anode of the X-ray tube 17.

The generator 15 is energized in advance of making an exposure with the X-ray tube 17 and charges the condensers 16 to its full open-circuit voltage, and then the exposure can be made at that voltage. In the absence of the capacitors 16, the power for energizing the X-ray tube 17 would come directly from generator 15, in which case the exposure voltage would be considerably below the open-circuit voltage of the generator 15 due to the regulation of the transformer therein, and the power line. The switching tube 11 and the insulation of the system also, in the absence of the capacitors 16, must withstand the full open-circuit voltage. Since the power for energizing the X-ray tube 17 comes from the capacitors 16, in accordance with this invention, instead of directly from the generator 15, the need to synchronize the exposure with the sine-wave of the power line is eliminated. With the present system the only time it may be desirable to synchronize the exposure with the power line frequencies might be in the event that it is desired to obtain a high rate of repetitive exposures. X-ray exposure current wave shape, pulse P1, is essentially identical to the shape of the voltage pulse P applied to the high voltage switching tube, the amplitude of the current being limited by the emission-limited characteristics of the X-ray tube 17.

In Fig. 2, all switches, relays, and the like are shown in the positions they occupy when the system of the present invention is installed in, but is not electrically switched into, the existing X-ray equipment and no power is applied to the system, line switch 41 being open.

The control grid bias and screen grid potentials of switching tube 11 are provided by an isolation transformer 18 with multiple secondaries, through suitable rectifiers 19-20 and filters. Transformer 18 also supplies filament power to all tubes in the high tension system except X-ray tube 17. The screen potential of switching tube 11 is supplied by rectifier 20 in a full-wave center-tap type of power supply embodying a simple filter capacitor 21 and bleeder resistor 22. The control grid negative bias supply consists of rectifier 19 in a second full-wave center tap type of power supply comprising a

filter capacitor 23, bleeder resistors 24 and 25, and a bias control tube 26. This bias control tube 26 is a tetrode which is operated at cut-off in its static condition and receives its grid bias and screen potentials from the voltage divider-bleeder resistors 24 and 25 which form part of the negative bias supply. A coupling capacitor 27 and control grid signal amplitude control potentiometer 28 are provided for driving tube 26 from the pulse transformer 12. The purpose of tube 26 is to provide a low impedance path for the control grid pulse current of the high voltage switching tube 11 and a high impedance path to the negative bias supply during the inter-pulse period, thereby reducing the average continuous current from the negative bias supply.

15 Control tube 26 minimizes driving power requirements by bypassing the current drawn by the control grid of the switching tube 11 around the bias supply during exposure periods.

Also shown in Fig. 2 is the safety circuit which is provided to protect the equipment from damage in the event of loss of negative bias on the switch tube 11 in case of power unit failure. This circuit consists of a voltage sensitive relay 29 and a current limiting resistance 30 across the negative bias supply, which relay 29 is actuated only when bias voltage is up to normal. Relay 29 closes the circuit to a signal light 31 which actuates a photocell 32 in an interlocked circuit, the chassis (not shown) which supports the photocell and associated circuitry being at ground potential.

20 The photocell circuit itself is basically of conventional design but possesses novelty in the present system by embodying a transparent glass or plastic rod or transilluminator R which is positioned between the photocell 22 and the signal light 31. Thus, the signal light 31, which is 25 part of the bias power supply, transmits light rays through the transilluminator R to operate the photocell 22. The transilluminator thus serves to electrically isolate the high tension circuitry from ground.

It will be understood that should the negative bias to 30 switching tube 11 fail for reasons such as, for example, short circuiting of the filter capacitor 23, burning out of the filament in rectifier 19, power failure in transformer 18, or for any other reason, this will cause relay 29 to open, thus turning off signal light 31 and stopping operation of photocell 32, thereby recovering negative bias on a thyratron tube 33 also in the circuit. Thyratron tube 33 operates on A.C. and, during operation of the system, is in a self-rectifying half-wave condition. Thus, the negative bias on the grid of thyratron tube 33, with falling plate voltage from the applied sine wave plate potential, allows this tube to turn itself off. This drops out plate relay 34, the contacts of which are in series with the coil of interlock relay 35. Such deenergizing of relay 35 opens its contacts which are in series with the coil of 35 a primary contactor 36, which is part of the existing diagnostic equipment with which the present system is used, which contactor 36 controls power to the high tension generator 15. This removes the high voltage which charges the pulse energy storage condensers or capacitors 16 as described hereinbefore.

A visual indication of loss of negative bias to the switching tube 11 is provided by a signal light 37 which is in a circuit to relay 34 and is energized when relay 34 opens.

In the absence of a safety device of this character, loss of negative bias and subsequent loss of control of the high voltage switching tube 11 would result in a continuing "runaway" condition, even after the initial discharge of the energy storage condensers 16, which might cause extensive damage to the system and particularly to the X-ray tube 17.

70 A relay 38 is provided to bypass the series safety circuits embodying relay 35 when, in a completed installation, the presently described system is turned off and not being used, so that the existing diagnostic unit into

which the present system is connected may be operated in the normal manner.

This system includes high tension switching means for completely disconnecting the high voltage elements of the switching tube circuitry so that conventional radiography techniques may be performed conveniently without requiring manual changes to be made after the system is installed in existing equipment. The high tension switching means consists of three ganged switches 39, 39a and 39b which are connected to an actuating mechanism which comprises two solenoids 40 and 40a. The switches 39, 39a and 39b in Fig. 2 are shown in positions permitting conventional use of the X-ray equipment, switch 39 connecting the anode of the X-ray tube 17 directly to the positive side of the high tension generator 15. It will be noted that at all times the cathode of the X-ray tube 17 is permanently connected to the negative side of the high tension generator 15.

To make radiographs with this system, it is merely necessary to close the line switch 41 which will cause energization of solenoid 40. Solenoid 40 thus will actuate switches 39, 39a and 39b, and thereby connect the present system into the existing X-ray equipment. Switch 39, in this position, connects the anode of the X-ray tube 17 to the cathode of the high voltage switching tube 11. Switches 39a and 39b now connect the high voltage sides of condensers 16 to the positive and negative sides respectively of the high voltage generator 15.

After sufficient time has elapsed to permit the various tubes in the system to reach operating temperatures, radiographic exposures may be made in a manner to be described hereinafter in connection with Fig. 3.

After all desired exposures have been made with the present system, the system may be turned off with line switch 41, which removes power from the system and, through solenoid 40a and time delay 42 which bypasses switch 41, the high tension switches 39, 39a and 39b are returned to their initial positions as shown in Fig. 2. The time delay 42 functions to remove power from the solenoid 40a after a predetermined time interval. High tension switches 39a and 39b now connect the high voltage side of the condensers 16 to discharging current limiting resistors 43 and 43a respectively.

A micro-switch 44 is mechanically actuated by the high voltage switching means and serves as a high voltage switch position safety interlock so that relay 35, which controls high tension generator primary contactor 36, will not close unless the high voltage switches have been completely closed to electrically insert this system in the existing equipment.

Signal lights are provided to indicate the proper or improper operation of or failure of power to the various circuits involved. Light 45 indicates that power is being supplied to the pulse-forming and timing circuit 10. Light 46 shows that power is being applied to power transformer 18 and the safety circuit described hereinbefore. Signal light 47 operates from microswitch 44 and indicates that the high tension switches 39, 39a and 39b are in proper position for operation of this system, while light 48 indicates, when lighted, that these switches are not properly positioned for this purpose.

A pulse monitor circuit 50 is incorporated in the pulse-forming and timing circuit 10 to indicate an exposure by the X-ray tube and to facilitate adjustment and calibration of the X-ray tube filament circuit by indicating the peak X-ray tube current in the presently described pulsed operation. The unit making up the pulse monitor 50 is essentially a peak voltmeter which reads the voltage drop across a current viewing resistor 49 in the center tap ground circuit of the energy storage capacitors 16.

Referring to Fig. 3, it is to be understood that the system of the present invention is adaptable for use with various types of conventional film changing devices. The present system may be used to control the film

changer or may be partially controlled by the film changer. For example, a film changer is indicated by numeral 51 in Fig. 3 and is shown connected to the pulse forming and timing circuit 10 through a manually operable selector switch 52 which allows selective manual or automatic control of the system. Switch 52 is shown in position to permit manual operation of the system whereby X-ray exposures may be made without using the film changer 51, the system being operated by manual closure of push button 53 to permit exposures to be made. When switch 52 is moved to the opposite position, this connects the film changer 51 into the system in such a manner that the film changer actually controls X-ray exposures to the extent that no exposures can be made, even when push button 53 is operated, until the film changer 51 has completed its automatic cycle. It is particularly pointed out that an operator has constant control of the device during the actual exposure cycles by being required to actuate push button 53 before any exposures can be made either manually or automatically.

An optional recycling circuit 54 can be provided for use with certain film changers where it is needed or desired such as, for example, in instances where the film changer will not function without a recycling signal or is not of the "free running" type. Such a recycling circuit 54 thus can be used to start operation of the film changer 51 after completion of an X-ray exposure.

Fig. 3 also shows that the pulse forming and timing circuit 10 receives power, when line switch 41 is closed, through the power supply 55. The primary power and control circuits 56 also receive power when switch 41 is closed and control the power to the high voltage equipment 57, as described in detail in connection with Fig. 2.

An example of one fundamental pulse forming and timing circuit capable of being used in this system is shown in Fig. 4. This circuit, indicated by numeral 10 in Figs. 1, 2 and 3, embodies a pulse generator for forming the substantially square pulses which are transmitted to the pulse transformer 12, and is adapted to form pulses of controlled width and voltage. A pulse amplifier is also included to increase the power level of the pulses developed by the generator, and a synchronizing trigger circuit is also embodied for initiating the formation of pulses by the generator when the push button 53 is manually operated.

The pulse generator may be of any suitable design and is shown in Fig. 4 as a driven monostable cathode-coupled multivibrator which is comprised, in this particular structure, of two triodes 58 and 59. This multivibrator is driven by a synchronizing amplifier tube 60 which is connected in parallel with tube 58.

The pulse width is manually adjustable over the desired range by means of a potentiometer 63 which varies the time constant of the timing control circuit of the multivibrator, which circuit includes a capacitor 64 as well as the potentiometer 63.

The pulses developed by the pulse generator are amplified by a vacuum tube amplifier 61 to a predetermined power level controlled by means such as a grid driving control potentiometer 62. The plate circuit of the pulse amplifier 61 is connected to the primary of the pulse transformer 12.

It is apparent from the foregoing description that a novel system has been provided for controlling the operation of an X-ray tube so as to obtain precisely timed exposures of five milliseconds or less, for example, in accordance with the objects of this invention. It is to be understood, however, that although the individual parts of the system have been shown and described specifically, many of these parts may be modified within the scope of this invention such as, for example, by substituting a thyratron or other pulse forming circuit for the pulse forming and timing circuit 10, or by use of

other types of rectified high voltage generators other than generator 15.

It is also to be understood that although a major portion of the preceding description relates to a system for controlling an X-ray tube so as to provide precisely timed ultra-short X-ray exposures, the system can be used for other purposes such as, for example, to apply pulses shorter than or longer than one millisecond to energy responsive devices of the type used in radar transmitters, particularly klystrons designed for operation at relatively high voltage levels. In some instances, also, the energy storage capacitors may be eliminated whereupon the power for energizing the energy responsive device will be provided directly from the generator.

Accordingly, while the novel features of the invention have been shown and described and are pointed out in the annexed claims, it is to be understood that various omissions, substitutions and changes in the details shown and described may be made by those skilled in the art without departing from the spirit of the invention. Therefore, it is to be understood that all matter shown or described is to be interpreted as illustrative and not in a limiting sense.

We claim:

1. A system for operating a high tension circuit embodying an energy responsive device by means of a low tension control circuit, comprising a generator in the high tension circuit, electrical energy storage means across the output of the generator and adapted to be charged to the full open-circuit voltage of the generator, one side of the energy storage means being connected to the energy responsive device, a high voltage switching tube of the tetrode type connected between the other side of the storage means and the energy responsive device, means connected with the switching tube for providing control grid bias and screen grid potentials thereon, pulse forming and timing means in the low tension circuit for generating a control signal in the form of an essentially square voltage pulse, and a pulse transformer between the high and low tension circuits adapted to receive the pulse from the pulse forming and timing means and to apply the pulse to the grid of the switching tube to cause discharge of energy from the energy storage means to the energy responsive device.

2. A system for operating a high tension circuit embodying an energy responsive device by means of a low tension control circuit, comprising a high voltage generator in the high tension circuit, electrical energy storage means across the output of the generator and adapted to be charged to the full open-circuit voltage of the generator, one side of the energy storage means being connected to the energy responsive device, a high voltage tetrode switching tube connected between the other side of the storage means and the energy responsive device, means connected with the switching tube for providing control grid bias and screen grid potentials thereon, a pulse forming and timing means in the low tension circuit for generating a control signal, a pulse transformer between the high and low tension circuits adapted to receive the control signal from the pulse forming and timing means and to apply the signal to the grid of the switching tube to cause discharge of energy from the energy storage means to the energy responsive device, and a safety circuit connected to the means for providing control grid bias to the switching tube comprising means for automatically discontinuing operation of the high voltage generator.

3. A system for operating a high tension circuit embodying an energy responsive device by means of a low tension control circuit, comprising a high voltage generator in the high tension circuit, electrical energy storage means across the output of the generator and adapted to be charged to the full open-circuit voltage of the generator, one side of the energy storage means being connected to the energy responsive device, a high voltage

tetrode switching tube connected between the other side of the storage means and the energy responsive device, means connected with the switching tube for providing control grid bias and screen grid potentials thereon, a pulse forming and timing means in the low tension circuit for generating a control signal, a pulse transformer between the high and low tension circuits adapted to receive the control signal from the pulse forming and timing means and to apply the signal to the grid of the switching tube to cause discharge of energy from the energy storage means to the energy responsive device, and a safety circuit connected to the means for providing control grid bias to the switching tube comprising a voltage-sensitive relay across the means for providing control grid bias and adapted to be closed when said means is functioning, a lamp connected with the relay so as to function when the relay is closed, a photocell in the low tension circuit, transilluminating means between the lamp and photocell for directing light from the lamp to the photocell, and means operable when the photocell is inoperative to break the circuit to the generator.

4. A system for operating a high tension circuit embodying an X-ray tube by means of a low tension control circuit, comprising a generator in the high tension circuit, electrical energy storage means across the output of the generator and adapted to be charged to the full open-circuit voltage of the generator, one side of the energy storage means being connected to the X-ray tube, a high voltage tetrode switching tube connected between the other side of the storage means and the X-ray tube, pulse forming and timing means in the low tension circuit for generating a control signal in the form of an essentially square voltage pulse, and a pulse transformer between the high and low tension circuits adapted to receive the pulse from the pulse forming and timing means and to apply the pulse to the grid of the switching tube to cause discharge of energy from the energy storage means to the X-ray tube.

5. A system for operating a high tension circuit embodying an X-ray tube by means of a low tension control circuit, comprising a generator in the high tension circuit, electrical energy storage means across the output of the generator and adapted to be charged to the full open-circuit voltage of the generator, one side of the energy storage means being connected to the X-ray tube, a high voltage switching tube of the tetrode type connected between the other side of the storage means and the X-ray tube, means connected with the switching tube for providing control grid bias and screen grid potentials thereon, pulse forming and timing means in the low tension circuit for generating a control signal in the form of an essentially square voltage pulse, and a pulse transformer between the high and low tension circuits adapted to receive the pulse from the pulse forming and timing means and to apply the pulse to the grid of the switching tube to cause discharge of energy from the energy storage means to the X-ray tube.

6. A system for operating a high tension circuit embodying an X-ray tube by means of a low tension control circuit, comprising a high voltage generator in the high tension circuit, electrical energy storage means across the output of the generator and adapted to be charged to the full open-circuit voltage of the generator, one side of the energy storage means being connected to the X-ray tube, a high voltage tetrode switching tube connected between the other side of the storage means and X-ray tube, means connected with the switching tube for providing control grid bias and screen grid potentials thereon, a pulse forming and timing means in the low tension circuit for generating a control signal, a pulse transformer between the high and low tension circuits adapted to receive the control signal from the pulse forming and timing means and to apply the signal to the grid of the switching tube to cause discharge of energy

from the energy storage means to the X-ray tube, and a safety circuit connected to the means for providing control grid bias to the switching tube comprising means for automatically discontinuing operation of the high voltage generator.

7. A system for operating a high tension circuit embodying an X-ray tube by means of a low tension control circuit, comprising a high voltage generator in the high tension circuit, electrical energy storage means across the output of the generator and adapted to be charged to the full open-circuit voltage of the generator, one side of the energy storage means being connected to the X-ray tube, a high voltage tetrode switching tube connected between the other side of the storage means and the X-ray tube, means connected with the switching tube for providing control grid bias and screen grid potentials thereon, a pulse forming and timing means in the low tension circuit for generating a control signal, a pulse transformer between the high and low tension cir-

5
